UNITED STATES PATENT OFFICE.

CHARLEY D. AGEE, OF DALLAS, TEXAS.

SHELF SUPPORT AND CARRIER.

Application filed March 31, 1926. Serial No. 98,873.

This invention relates to new and useful improvements in shelf supports and carriers.

The object of the invention is to provide a shelf support and carrier of a simple and practical nature embodying certain novel and advantageous features.

A particular object of the invention is to provide a spring mounted carrier for the shelf, whereby the latter is resiliently supported and may be readily folded into a closed position and effectually held in such position.

Another object of the invention is to provide spring means arranged to function when the shelf approaches the completion of its unfolding swing, thus cushioning the unfolding movement and preventing slamming and harsh action.

A construction designed to carry out the invention will be hereinafter described with other features of the invention.

The invention will be more readily understood from a reading of the following specification and by reference to the accompanying drawings, in which an example of the invention is shown and wherein:

Fig. 1 is a front elevation of a structure constructed in accordance with my invention.

Fig. 2 is a vertical sectional view of the same taken on line 2—2 of Fig. 1.

Fig. 3 is a detail of the carrier mounting and the retarding spring attachment.

Fig. 4 is a detail of the carrier connection.

Fig. 5 is a perspective view of one of the carriers.

Fig. 6 is a cross-sectional view taken on the line 6—6 of Fig. 2.

Fig. 7 is a front elevation of an ironing board structure constructed in accordance with my invention.

Fig. 8 is a vertical sectional view through Figure 7 with the shelf opened for use.

Fig. 9 is a partial vertical sectional view and the door closed, and

Fig. 10 is a cross-sectional view taken on line 10—10 of Fig. 7.

In the drawings, the numeral 10 designates the back wall of a vertical casing or cabinet having side walls 11 and set into the wall of the building. A facing frame 11' is secured to the front edge of the casing and overlies the wall in which the casing is set. A cross member or header 12 is se-

cured to the frame at the central portion thereof. The casing is closed below said member and is open above said member.

The side walls 11 have vertical grooves or channels 13 and coiled springs 14 lying in the channels having their upper ends supported at 15. The lower end of each spring is fastened in a U-shaped metal carrier 16 having a depending ear 17. The ears are pivoted to the ends of a transverse cleat 18. The cleat is fastened across the back of a shelf 19, which is adapted to be swung down to a horizontal position as is shown in the dotted lines in Fig. 2.

When the shelf is swung down it will rest upon the member 12 and its inner end will catch under a transverse stop 20 secured to the back wall 10, whereby said shelf will be securely supported. The term "shelf" is used generically herein, as it may be a shelf, a seat, an ironing board, a desk leaf or any other horizontal supporting element. It will be seen that the springs 14 will yield to a downward pressure, but will pull the shelf up to a proper position.

The side walls 11 project from the casing frame and the shelf closes against this projection. Below the member 12, the shelf has a reduced portion 19a, which when the shelf is swung outward, swings inward between the side walls 11. In order to cushion and retard the downward swing of the shelf, I provide swinging stop arms 21 and retarding coiled spring 22 pivoted at their lower ends to the forward ends of the arms. The arms are pivoted to the side walls 11 and their upward travel limited by stops 23. The upper ends of the springs are connected to rings 24 loosely confined in slots 25 upon pins 26.

Then the shelf is swung outward and downward, the springs 22 will be lifted and in turn will swing the arms 21 upwardly. As the shelf approaches its horizontal position, the arms will engage with the stops and further movement of the shelf will tension said springs. This action will retard and cushion the completion of the swing. It will be seen that the springs 14 will exert an upward pull on the shelf so that its inner end will fit up close to the stop 20 and the weight of the outer portion will cause it to rest firmly on the member 12.

In Figs. 7 to 10 inclusive, I have shown the shelf in the form of an ironing board.

On top of the member 12 is a table 12'. The cleat 18' is fastened to the front of the board instead of to its back and places the board within the casing when it is swung upward. A door 31 is hinged or otherwise secured in the frame 11' above the table for closing the casing when the board is not in use. Instead of the rings 24, ordinary screw eyes 32 are used at the lower end of the board to attach the springs 22. The operation is the same as in the other form.

Various changes in the size and shape of the parts as well as modifications and alterations may be made within the scope of the 15 appended claim.

What I claim is:—

The combination with an upright casing having vertical channels at each side therein, coiled springs suspended in said channels, a swinging shelf pivoted to the lower ends of said springs by means of carriers embracing the spring and having a lug pivoted to the shelf, a fixed stop on the inner back wall of the casing, arms pivoted in the casing to its sides, stops on the inner sides of the casing within the paths of the arms, and coiled springs attached to the arms and the inner end of the shelf.

In testimony whereof I affix my signature.

CHARLEY D. AGEE.
